Primary Examiner—Mitchell Siegel(74) *Attorney, Agent, or Firm*—Nixon & Vanderhye P.C.(57) **CLAIM**

The ornamental design for a dragline bucket, as shown and described.

DESCRIPTION

FIG. 1 is a front isometric view of an embodiment of a dragline bucket showing my new design.

FIG. 2 is a front elevational view thereof.

FIG. 3 is a rear elevational view thereof.

FIG. 4 is a right-side elevational view thereof, the left-side elevational view being a mirror image.

FIG. 5 is a top plan view thereof; and,

FIG. 6 is a bottom plan view thereof.

Background features (such as flooring and adjacent fixtures), Alphanumeric characters, other incidental markings and any features indicated in broken lines in the accompanying drawings form no part of the claimed invention. In particular, the shape and configuration of the hoist rope mounting points (seen as inwardly angled upper flanges with rows of seven holes), drag rope mounting points (seen as forwardly extruding flanges with rows of three holes) and cutting teeth form no part of the claimed invention.

FIG. 1

FIG. 2

FIG. 3

FIG. 4

FIG. 5

FIG. 6
